UNITED STATES PATENT OFFICE.

JOHN KARSSEN, OF HOLLAND, MICHIGAN.

COAL-HOD.

1,234,671.

Specification of Letters Patent. Patented July 24, 1917.

Application filed March 9, 1917. Serial No. 153,641.

To all whom it may concern:

Be it known that I, JOHN KARSSEN, a citizen of the United States, and a resident of Holland, in the county of Ottawa and 5 State of Michigan, have invented an Improvement in Coal-Hods, of which the following is a specification.

My invention is an improvement in coal hods, and has for its object to provide a 10 hod of the character specified, that may be filled with coal and set upon the top of the stove, and is so constructed that the coal may be shoveled out at the bottom of the hod on a level with the top of the stove.

15 In the drawings:

Figure 1 is a perspective view of the improved hod.

Fig. 2 is a vertical section.

The present embodiment of the invention 20 comprises a body portion of hopper shape, comprising end walls 1, a rear wall 2, and a front wall 3, the said walls 2 and 3 being spaced apart at their bottoms to form an outlet, and the wall 3 is continued below 25 the wall 2, as indicated at 4, for a purpose to be presently set forth.

The hod is provided with the usual bail 5 for convenience in handling the same. The hod has an extension consisting of a 30 bottom 6 and side walls 7, which are continuous with the walls 1, and a rear wall 8, which is continuous with the wall 2. The bottom extends forwardly and rearwardly of the hopper-shaped body, a greater distance forwardly, however, than rearwardly, 35 and the extension 4 of the wall 3 is spaced above the bottom 6, as shown, to provide an outlet for the coal into the open container formed by the bottom and the side 40 walls 7.

A front wall 9 is provided for the extension, the said wall being high enough to prevent the falling out of the coal in the extension, but not so high as to interfere 45 with the insertion of a shovel into the extension and into the space behind the ex-

tension 4 of the front wall 3. It will be noticed that the lower end of the extension 4 is curved rearwardly, as indicated at 10, to deflect the coal into a species of hood 50 formed by the walls 7 and 8 at the rear of the hopper. The hopper in its entirety comprises the body and the extension which is a shovel-way for permitting the insertion of a shovel into the bottom of the hopper. 55

In use, the hod is filled with coal, and seated on the top of the stove, the improved hopper being especially designed for use with kitchen stoves and ranges, and with the open portion of the extension at the 60 front. A shovel may be now inserted into the extension, and the coal shoveled out into the open stove.

The extension forms a species of tray or shovel board, upon which the coal may drop 65 from the body of the hod, and from which it may be easily removed by the shovel.

I claim:

A coal hod comprising a hopper shaped body consisting of substantially parallel 70 end walls, and front and rear walls converging toward the bottom of the body and spaced apart to form an opening at the bottom, an extension consisting of side walls continuous with the side walls of the body, 75 and a rear wall, the said side walls of the extension extending rearwardly beyond the rearmost portion of the rear wall and forwardly well beyond the foremost portion of the forward wall, the said extension being open at the front and having an upstanding flange between the side walls at its forward end, the front wall of the body being extended below the tops of the side walls of the extension approximately half 80 the depth of the said side walls and being curved rearwardly at its free edge for the purpose specified.

JOHN KARSSEN.
